UNITED STATES PATENT OFFICE

2,329,941

SHIP WITH CONVERTIBLE PLATFORM

Salem Elihu Posin, Brooklyn, N. Y.

Application January 15, 1943, Serial No. 472,441

14 Claims. (Cl. 114—43.5)

My invention relates to the structure of ships, and its main object is a ship comprising a platform which can be lowered into the ship's main body when not used and which can be raised and brought into operating position over the ship's main body and, then forms a large horizontal area adapted for launching or landing of airplanes, for tennis or other plays, or for any other purpose requiring a large even surface.

Conventional aircraft carriers equipped with permanently fixed platforms have several drawbacks restricting the usefulness and efficiency of the ship. For example, a conventional aircraft carrier can easily be spotted and identified by the enemy, the air resistance and the impact of vertical or oblique squalls is increased by the platform, and the stability and speed is inferior to ordinary ships. Objects of my invention are to avoid the drawbacks of permanently fixed platforms when the use of the platform is not necessary, and to create a type of ship which can be converted into an aircraft carrier or be provided with a large free platform, but which can be used as well as any ordinary ship when not converted in said manner.

Further objects are to make said conversion easy and quick, to provide means therefor which require low power and low expenses and which occupy only a small space, and to provide a structure of the platform and its accessories which can be easily and inexpensively built into an ordinary ship or can be provided when a new ship is built without much alteration of the ordinary design.

Other objects are to equip a ship of said type with a platform which can be turned from a horizontal position to a vertical position, to provide a slot in the ship's body receiving the vertically positioned platform, to provide means raising said platform into horizontal position and means supporting the platform safely when the latter is in horizontal position, and to conceal all these means under the horizontal platform. Still other objects are to make the platform foldable, to reduce the depth required for the slot, and to cover the slot when the platform is lowered.

Still further objects are means whereby airplanes or other objects can be moved to and from the level of the platform and can be stored under the platform or within the ship, adaptation of the inventive device to different types of ships, and a plurality of ships having platforms of the kind mentioned before which platforms can be connected into one larger platform.

Other objects will appear from the following

description of exemplifying embodiments, the drawings illustrating the same and the claims.

According to the invention, the ship has a deck provided with at least one vertical slot extending down into the ship's body and receiving a platform turned into vertical position. Further features of the invention are described in this specification, specifically pointed out in the appended claims, and illustrated in the accompanying drawings in which:

Fig. 1 shows an exemplifying embodiment of ship according to the invention, seen from above and having the platform in operating position;

Fig. 2 shows the same embodiment seen from the side;

Fig. 3 shows a cross-section of the same embodiment, on a larger scale, said cross-section taken along the line 3—3 in Fig. 1, the platform being shown raised, but not yet completely brought into the horizontal operating position;

Fig. 4 shows a plan view of a broken off portion of the ship, on a scale smaller than that of Fig. 3 and larger than that of Figs. 1 and 2, the ship's wall being cut along the line 4—4 in Fig. 3;

Figs. 5, 6, 7 and 8 show details of the same embodiment, on a scale larger than that of the preceding figures;

Fig. 5 showing a horizontal view of the top end of the raising device;

Fig. 6 showing a partly sectional vertical view of details shown in Fig. 5, said section taken along the line 5—5 in Fig. 5.

Fig. 7 showing a plan view of a broken off corner of a platform section;

Fig. 8 showing a cross-section through a broken off portion of the platform, said cross-section taken along the line 8—8 in Fig. 7;

Fig. 9 shows a vertical side view of a ship representing a modified embodiment of the invention, on a reduced scale;

Figs. 10, 11 and 12 show horizontal views seen from above of three other modifications.

In all figures, some details have been omitted and some measures have been exaggerated in comparison to other measures where this has been deemed desirable for the sake of clearer representation.

Referring to the embodiment shown in Figs. 1 to 8, numeral 1 indicates the ship's body, the upper surface of which is formed by the deck 2. A number of posts or stanchions 3 stand along the edge of the deck 2 and support the platform 4 when the latter is in the horizontal position shown in Figs. 1 and 2. Further supporting

means are provided under the middle of the platform 4 as will be described later.

The platform 4 is divided across the length of the ship into four sections 5, 6, 7 and 8, each comprising two symmetrical parts or wings 9 and 10 which, when in vertical position, are folded together. A vertical slot or channel 11 extends downward from the deck 2 into the ship's body and receives the platform in folded condition. Each section may be separately lowered into or raised out of the slot 11 as will be described later.

The ship is equipped with one or more hoisting devices or cranes, for example, with a mast 12 having a horizontal arm 13 carrying a hook 14 at which a load may be suspended, for example, by means of a block-and-pulley device, or the hook itself may be movable in vertical direction in any conventional manner. Said suspended load, for example an airplane, can be lowered from the level of the platform 4 to the deck 2 or deeper into an opening of the ship's body after that section of the platform which is situated under the hook 14 has been folded. Then the load may be moved into a storing position either on the deck 2 or in the ship. The reverse operation is performed when a load is to be moved from a storing position to the platform. Due to the sectional structure of the platform, these operations require the movement of only a part of the platform, and the remaining part of the platform provides instant and lasting protection for the loads stored thereunder.

A number of vertical rails or posts 15 stand on the deck 2, arranged in pairs at both sides of the slot 11. Each rail 15 has a U shaped cross-section, the opening of the U being directed to the outer side and the flat back of the U being in line with the side of the slot 11 (Fig. 3). A bracket 16 is affixed to each rail 15 and has a bore in which a shaft 17 is rotatably mounted. The shaft 17 carries two rollers or pulleys 18, each serving one of two adjacent platform sections. At the end of the platform where only one section is to be served, similar rails are positioned, but each of the latter carries only one roller 18.

Blocks or sleds 19, each having about the width (in the longitudinal direction of the slot 11) of a roller 18 can slide vertically from the bottom of the slot 11 to the upper end of the rails 15, one block 19 being provided for each end of each platform section. Each block 19 has an upper extension 20 equipped with a joint where the two wings 9 and 10 of one platform section are linked.

The rollers 18 which are situated at one side of the slot 11 (left side in Figs. 3, 5 and 6) have peripheral grooves carrying ropes or chains 21 having one end attached to the upper side of the corresponding block 19. From this point, the rope 21 runs over the grooved roller 18, then downward and over a pulley 22 from which the rope runs upward to its other end attached to the lower side of the same block 19. Rotation of the pulley 22 pulls the block 19 by means of the rope 21 up or down. In the position shown in Fig. 3, the block 19 has not quite reached its uppermost position, and the wings 9 and 10 are resting in an oblique position against the outer surface of the corresponding rollers 18. A slight further upward movement of the block 19 will lower the free ends of the wings until they come to rest on the posts 3. In the latter position, the wings form one horizontal platform supported by the rollers 18 and the posts 3. The support may be made resilient by covers of elastic material su-

perposed to the upper ends of the posts 3, to the outer surface of the rollers 18 or to both, or affixed to the touching lower surfaces of the wings.

Lowering of the blocks 19 will pull the inner ends of the wings 9 and 10 downward and will cause the outer ends to raise while the wings slide or roll along the rollers 18 until the two wings are folded together in a vertical position. Further lowering of the blocks draws the folded platform section vertically downward until the same has reached the lowermost position and further movement is stopped. In the shown embodiment, the folded section can be completely drawn into the ship's body, and then, the upper end of the section closes the slot 11 and flushes with the deck 2. In modified embodiments, the slot may be less deep and the platform, in its lowermost position, may extend somewhat over the deck 2.

When the block 19 is moved upward again, the wings are raised and start to unfold when their lower ends have passed the upper end of the rails 15. While unfolding, the wings are guided along the rollers 18.

A counterweight 23 is attached to the rope 21 and is raised when the platform is lowered or vice versa whereby the power necessary for raising the platform is reduced. The weight 23 continues going down when the wings drop to the horizontal position whereby the whole system has a lower center of gravity when the platform is used than when it is concealed. This fact increases the stability of the ship because loads positioned on the platform will raise the center of gravity of the ship. The relatively high position of the load when the platform is used may be compensated also by other means, for example, by a pump 24 which shifts fuel or ballast from higher tanks 25 through pipes 27, 28 to lower tanks 26 when the platform is raised and vice versa when the platform is lowered. Left and right tanks 25 and 26, respectively communicate by pipes not visible in the drawings.

The decks or floors have openings 29 for the passage of the counterweight 23. A lid 30 slotted for the passage of the rope 21 can be turned around in order to cover the opening 29 in the deck 2 when the platform section is not to be moved. Suitable or conventional means may be provided which allow to fix the platform section in either of the end positions or also in any intermediate position.

A shaft 31 rotatably carried by bearings in brackets 32 extends longitudinally through the ship (Fig. 4) and can be driven in any suitable manner not shown, preferably by a gear deriving power from the ship's main engine which is located at the rear (funnel) end of the ship. A hand crank may be provided for use in emergencies or instead of the motor drive.

The shaft 31 carries a pulley 33 which, when coupled to the shaft 31, drives the reversible pump 24 having a pulley 34 connected by a belt to the pulley 33.

The shaft 31 carries further pulleys 35, one pulley 35 being provided for each platform section. Every pulley 35 can be separately coupled to the shaft 31 and then drives a pulley 36 affixed to a parallel shaft 37 supported by bearings in brackets 38. There is one shaft 37 for each platform section, all said shafts 37 being co-axial, but separated from each other. Each shaft 37 carries two of the pulleys 22 mentioned before. These two pulleys are connected to the shaft 37 and turn simultaneously when the corresponding pulley 35 is coupled, thereby driving two ropes 21,

two blocks 19 etc. as described before. It appears that coupling of one pulley 35 will move one section of the platform and that coupling of all pulleys 35 will move the entire platform.

Figs. 5 and 6 show the upper end of the raising device and the upper end of the platform section in a vertical folded position not yet raised far enough for unfolding. In the shown embodiment, the structure of a platform section comprises a large number of spaced beams, or bars 38 (Figs. 7 and 8) with U-shaped cross-sections and flat, alined upper surfaces, the flat surfaces of corresponding wings touching each other in the folded position. This spaced arrangement of the beams has the advantage that the surface of the platform offers a certain resistance to a rolling aircraft, whereby the landing way is reduced. If the spaces between the beams are sufficiently wide, the structure may be so modified that two corresponding wings fold into each other. The end beams 39 of each section have an angular and thicker cross-section and are adapted to roll over the rollers 18 as described before.

All beams of one section are connected by a number of parallel elements extending perpendicularly to the beams 38 in the direction of the ship's length. These elements are represented by tubes 40 in the shown embodiment. In addition, the outer edges of the beams 38 and 39 are connected by a flat rim 41 which, in the horizontal position, falls over the posts 3, and, in the concealed position, closes the slot 11. The rims 41 of the sections 9 have small slots 42 for the passage of the ropes 21. The entire platform is preferably made of steel, each section being welded together. Or any other suitable material or structure may be used.

Referring to Fig. 9, a platform 104 raised over a slotted deck 102 forms a horizontal continuation of a higher deck 103 of the same ship. In this modified embodiment, the deck 103 is a part of the total available platform area which part is permanently in horizontal position and may be equipped with devices and openings for moving airplanes etc. from or to the level of the platform. The details of the invention not shown in Fig. 9 are similar as the details described with reference to Figs. 1 to 8.

Fig. 10 shows two ships of the kind described with reference to Figs. 1 to 8. These two ships are anchored in parallel position, and their unfolded platforms are connected into one broader platform. This modification makes it possible to use ships for the operation of aircraft which are singly not big enough to carry a sufficiently large landing platform.

The modification shown in Fig. 11 differs from those shown in the other figures in that the slots 111 and 112 are directed across the ship instead of lengthwise. The same figure illustrates another modification consisting of two alined enlargements 113 of a part of the ship situated over the water line. The slot 111 extends beyond the original edge of the slotted deck into said enlargements 113.

Certain ship types, for example, tankers, are usually so designed that the funnel, engine and bridge are near the rear end of the ship, and the so far described embodiments have been illustrated in connection with such ship types. The use of a ship of this tanker type, however, is no indispensable feature of the invention and the latter may be applied to other ship types. For

example, Fig. 12 shows a modification comprising a ship with a central funnel 50. This modification has two parallel rows of platform sections 51 and 52, the sections 51 being foldable at the line 53, and the sections 52 being foldable at the line 54. The two rows are resting on common posts arranged under the line 55. Two longitudinal slots, each for the reception of one row of sections, are situated under the lines 53 and 54. These wings of the platform sections which surround the funnel 50 are recessed or cut out as at 56 to allow for the free passage of the funnel. Other recesses 57 surround the bridge or other parts towering over the platform.

Other modifications can be made by anyone skilled in the art without departing from the spirit of my invention, and I desire it understood that my invention is not confined to the forms and uses described as the same are only a few of the many that can be employed to carry out the invention.

Having now described my invention, what I claim and desire to secure by Letters Patent is:

1. A ship having a floating body with a deck forming an upper surface of said body and with a slot extending from said deck into said body, a movable platform, means supporting said platform when said platform is in a horizontal position over said deck, and means to move said platform from said horizontal position into said slot and out of said slot into said horizontal position.

2. A ship having a floating body with a deck forming an upper surface of said body and with a vertical slot extending from said deck into said body, a movable platform substantially covering said deck in a horizontal position over said deck, means supporting said platform when said platform is in said horizontal position, and means to move said platform from said horizontal position into said slot and out of said slot into said horizontal position.

3. A ship having a floating body with a deck forming an upper surface of said body and with a slot extending from said deck into said body, a foldable and vertically movable platform, means supporting said platform when said platform is in an unfolded horizontal position over said deck, and means to move said platform in folded condition into and out of said slot.

4. A ship having a floating body with a deck forming an upper surface of said body and with a slot extending from said deck into said body, a movable platform comprising a plurality of separate sections, means supporting said platform sections in equally high horizontal positions over said deck, and means to move each of said platform sections separately from said horizontal position into said slot and out of said slot into said horizontal position.

5. A ship having a floating body with a deck forming an upper surface of said body and with a slot extending from said deck into said body, a foldable and vertically movable platform comprising a plurality of separate sections, means supporting said platform sections in equally high, horizontally unfolded positions over said deck, and means to move each of said platform sections separately in folded condition into and out of said slot.

6. A ship having a floating body with a deck forming an upper surface of said body and with a slot extending from said deck into said body, a movable platform, means supporting said platform when said platform is in a horizontal posi-

tion over said deck, and means completely confined to the space under the upper level of said platform and adapted to move said platform from said horizontal position into said slot and out of said slot into said horizontal position.

7. A ship having a floating body with a deck forming an upper surface of said body and with a slot extending from said deck into said body, a movable platform comprising a large number of parallel spaced beams connected by crossing elements, means supporting said platform when said platform is in a horizontal position over said deck, and means to move said platform from said horizontal position into said slot and out of said slot into said horizontal position.

8. A ship having a floating body with a deck forming an upper surface of said body and with a slot extending from said deck into said body, a movable platform, means supporting said platform when said platform is in a horizontal position over said deck, means to move said platform from said horizontal position into said slot and out of said slot into said horizontal position, and a rim affixed to said platform at an edge parallel to said slot, and sufficiently broad in a direction perpendicular to the surface of said platform to cover said slot when said platform has been moved into said slot.

9. A ship having a floating body with a deck forming an upper surface of said body and with a slot extending from said deck into said body, a movable platform comprising a plurality of separate sections, means supporting said platform sections in equally high horizontal positions over said deck, means to move each of said platform sections separately from said horizontal position into said slot and out of said slot into said horizontal position, and a hoisting device extending over one of said platform sections.

10. A ship having a floating body with a deck forming an upper surface of said body and with a slot extending from said deck into said body, a movable platform, means supporting said platform when said platform is in a horizontal position over said deck, means to move said platform from said horizontal position into said slot and out of said slot into said horizontal position, and a weight movable in response to the movement of said platform and over compensating that verti-

cal shift of weight which is caused by the movement of said platform.

11. A ship having a floating body with a deck forming an upper surface of said body and with a slot extending from said deck into said body, a movable platform, means supporting said platform when said platform is in a horizontal position over said deck, means to move said platform from said horizontal position into said slot and out of said slot into said horizontal position, and rails extending from said slot upward and guiding the movement of said platform when said platform is in vertical position over said slot.

12. A ship having a floating body with two decks forming two differently high upper surfaces of said body and with a slot extending from the lower of said decks into said body, a movable platform, means supporting said platform when said platform is in a horizontal position flushing with the higher of said decks, and means to move said platform from said horizontal position into said slot and out of said slot into said horizontal position.

13. A combination of two ships, each having a floating body with a deck forming an upper surface of said body and with a slot extending from said deck into said body, a movable platform, means to support said platform when said platform is in a horizontal position over said deck and means to move said platform from said horizontal position into said slot and out of said slot into said horizontal position, the two platforms of said ships having the same level, when supported in horizontal position, and being temporarily connected to each other.

14. A ship having a floating body with a deck forming an upper surface of said body and with a slot extending from said deck into said body, a movable platform, means supporting said platform when said platform is in a horizontal position over said deck, means to move said platform from said horizontal position into said slot and out of said slot into said horizontal position, and an enlargement of that part of the ship's body which is in the direction of said slot, said slot extending beyond the edge of said deck into said enlargement.

SALEM ELIHU POSIN.
